United States Patent

Des. 236,061
Patented July 29, 1975

236,061

CHAIR BASE

William H. Tacke, Wyoming, Mich., assignor to Curtis
Products Ltd., Cobourg, Ontario, Canada

Filed Dec. 3, 1973, Ser. No. 420,978

Term of patent 14 years

Int. Cl. D6—06

U.S. CL. D6—196

FIG. 1.

FIG. 2.

FIG. 3.

FIG. 4.

FIG. 1 is a perspective view of a chair base embodying the design of my invention;

FIG. 2 is a front elevational view of the base;

FIG. 3 is a side elevational view of the base; and
FIG. 4 is a top plan view of the base.

I claim:

The ornamental design for chair base, substantially as shown.
